PACKAGING FOR FRANGIBLE OBJECTS

Mansfield F. Ritchie, Benton Harbor, Mich., assignor to Twin Cities Container Corporation, Benton Harbor, Mich., a corporation of Michigan

Application December 1, 1950, Serial No. 198,639

3 Claims. (Cl. 206—65)

1

This invention relates generally to improvements in packaging, and relates particularly to an improved carton for packing a frangible object, such as an object made of refractory material, in such a fashion as to space the object from the sides, top and bottom of its shipping container with equal pressure against all sides of the object at all times.

In the packing of frangible objects, such as might be made from refractory materials, it has heretofore been the practice to wrap the objects in several thicknesses of padding and to enclose the wrapped article in a carton with the wrapped article spaced from the top, sides and bottom by additional pads, wadded paper, excelsior or the like. Such modes of wrapping and packaging are costly and extremely messy, and are also not entirely practicable from the standpoint of breakage.

According to the present invention it is possible to package a more or less irregularly shaped object such as a split fire pot ring assembly made of refractory material, and to support the parts making up such an assembly in such a fashion that the several parts are completely spaced from the walls of the container and securely held in position therein, irrespective of whether the container rests on its sides or on the top or bottom thereof. According to the present invention the objects to be packed, which in the instant application are in the form of a pair of rings, each of which is split along a diameter thereof, are supported on a tray having sides which extend along the inner side of the carton and bear against the bottom flaps of the carton. The split ring is supported on the tray and is held against displacement from side to side by die cut support sheets having cutout portions closely fitting the split ring segments and holding the ring segments in spaced relationship. One of the support sheets is provided with flanges or tabs which are turned down to extend along opposite inner sides of the container and to bear against the tray. The second support sheet is die cut in a fashion similar to the first and so as to hold two of the mating half ring portions within the confines of the cut out portions, and at the same time is turned through a 90° angle so that its direction of greatest strength is at 90° to the direction of greatest strength of the first support sheet. The second support sheet is likewise provided with bent over flanges or tabs which lie alongside the inner sides of the carton, and which bear against a top tray resting on top of the ring segments which are so supported by the support sheets.

2

In the preferred embodiment of the present invention a pair of such split rings are supported within the container body, and a divider pad is employed to separate each pair of split rings from the other. Accordingly, the upturned flanges of the second support sheet bear against the underside of the divider pad, and also extend along the opposite inner sides of the carton. The second of the pair of split rings rests upon the divider pad referred to, and support sheets similar to those supporting the first of the pair of split rings are provided to hold the second of the pair of split rings in position against lateral movement. Thus, a third support sheet is provided with downward extending flanges or tabs which extend along the inner sides of the carton and bear against the divider pad. A fourth support sheet underlies the third support sheet and is spaced therefrom to provide for lateral support of the second of the pair of split rings. The fourth support sheet likewise has a pair of upward extending flanges which extend along the opposite inner sides of the container body and bear against a tray resting upon the second of the pair of split rings, the tray having sides extending along the inner sides of the carton, and bearing against the folded top flaps of the carton.

It is a principal object of the invention to enable a frangible object to be packed in such a fashion that the object is completely isolated or spaced from the sides, top and bottom of its shipping container.

Another object is to afford a simple arrangement for packing an irregular shaped frangible object in such a fashion as to space the object from the sides, top and bottom of its shipping container, and to achieve such packing of the article by the use of flat sheets of fiber or corrugated box board which are suitably die cut and scored to fit within a conventional flat sided container.

Still another object of the invention is to provide a construction for a container or package for a number of articles which together make up an assembly such as a fire pot ring assembly formed from split rings which are extremely frangible, and to support the various elements making up such an assembly in such fashion that the various elements are completely separated from each other and are completely spaced from the sides, top and bottom of the container.

Other important objects and features of the present invention will be apparent from a study of the following description taken together with the drawings which together illustrate a pre-

ferred embodiment of the invention, and what is now considered to be the best mode of applying the principles thereof. Other forms of the invention as fall within the purview and the spirit and scope of the appended claims are intended to be reserved.

In the drawings:

Figure 1 is a plan view of one of a pair of split rings formed from a frangible refractory material and forming part of a fire pot lining, showing one the split rings held in position in a container according to the present invention, the top of the container being removed for purposes of illustration;

Figure 2 is a vertical cross-section taken along a vertical plane along the line 2—2 of Figure 1, just inside a side wall of the container, and looking in the direction of the arrows and showing the manner of disposing the pair of split rings within the container;

Figure 3 is a horizontal section taken through the container shown in Figure 2 along the line 3—3 and looking in the direction of the arrows; and

Figure 4 is an exploded isometric view showing the container according to the present invention with the frangible object shown in position therein.

Referring now to the drawings, the improved container according to the present invention is indicated generally by the ordinal 10 and is fabricated in part from a cut and scored sheet to define continuous side walls 11 to 14, walls 11 and 14 being joined along their contiguous edges by a strip of gummed fabric 16 in a manner known to those in the art. The container 10 is provided with upper end flaps 17 to 20 extending from the top of the walls 11 to 14, and the end flaps are folded over in the manner shown and held together by a strip of gummed tape or fabric 21 to define a closure for the top of the carton 10. The container body 10 is also provided with lower end flaps 22 to 25 extending from the bottom of the walls 11 to 14, and the end flaps 22 to 25 may likewise be folded over and held together along their contiguous edges by a strip of gummed tape or fabric 26 extending for the length of the flaps 24 and 25 to define a bottom closure for the carton 10.

According to the present invention, the carton 10 is adapted to enclose a fire pot ring assembly made of a frangible refractory material in such a fashion that the parts making up the assembly will at no time be subjected to any blows against the sides, bottom or top of the container 10 incident to the handling or transport thereof.

The fire pot ring assembly is made up of split rings which when cemented together and positioned one atop the other define a tiered fire pot ring. The container body 10 is thus adapted to support a lower ring composed of a pair of ring segments 27 and 28 formed at the ends thereof as at 29 so as to key together. The container body 10 may also be so constructed to support an upper ring composed of a pair of ring segments 31 and 32 also formed at the ends thereof as at 33 so as to key together.

The lower ring is adapted to rest upon an inverted tray 34 having sides 36 which bear against the inside folded bottom flaps 22 and 23, and which extend along the inside of the sides 11 to 14.

Means are provided for enabling the ring segments 27 and 28 to be supported upon the inverted tray 34 in position spaced from each other and from the sides 11 to 14 of the carton 10, and

in such a fashion that the ring segments will be incapable of rocking individually or together upon the inverted tray 34. To this end a pair of support sheets 37 and 38 are provided which are spaced from each other in their substantial planes, and which have flanges extending in opposite directions to limit the amount of possible movement of the support sheets toward and away from each other.

The support sheet 37 is thus cut with a pair of arcuate slots 39 and 41 of a size corresponding to the cross-section of the respective ring segments 27 and 28 so that the support sheet 37 will closely fit the ring segments 27 and 28. The centers of the arcuate slots 39 and 41 are spaced a small distance so that the support sheet 37 is continuous across the ends 29 of the ring segments 27 and 28 as seen at 42, so that the sheet 37 presents a die-cut web for holding the ring segments 27 and 28 against lateral displacement with respect to the sides 11 to 14 of the container 10.

The support sheet 37 is adapted to be properly spaced from the inverted tray 34 by flanges 43 which bear against the inverted tray 34 and which extend along the inner sides of the walls 11 and 13 of the carton 10.

The support sheet 38 is likewise cut with a pair of arcuate slots of a size corresponding to the cross-section of the ring segments 27 and 28, and are so disposed in the support sheet 38 as to be in register with the arcuate slots 39 and 41 cut in the support sheet 37. As shown in the several views the sheet 38 is so related with respect to the sheet 37 that its fiber grain is at 90° with respect to the grain of the sheet 37. In the case of corrugated sheet material the corrugations of sheets 37 and 38 would be at right angles with respect to each other.

As seen in the drawings the sheet 38 underlies the sheet 37 and is held in properly spaced relationship with respect to the sheet 37 by upturned flanges or tabs 44 which extend along the inner sides of the side walls 12 and 14 of the carton 10. In the preferred embodiment of the invention the tabs 44 bear against a divider pad 46 which rests upon ring segments 27 and 28, and which provides a support for the ring segments 31 and 32. The divider pad 46 is of such dimension as to fit the inside of the walls 11 to 14 closely.

The split ring sections 31 and 32 which rest upon the divider pad are preferably arranged so as to be related 90° with respect to the split rings 27 and 28. The ring segments are likewise supported in such a fashion that the ring segments 31 and 32 will be incapable of rocking individually or together upon the divider pad 46. To this end a similar pair of support sheets 47 and 48 are provided which are spaced from each other in their substantial planes, and which have flanges or tabs 52 and 54, respectively, extending in opposite directions to limit the amount of possible movement of the support sheets 47 and 48 with respect to each other.

The support sheet 47 is cut with a pair of arcuate slots 49 and 51 of a size corresponding to the cross-section of the respective ring segments 31 and 32 so that the support sheet 47 will fit the ring segments 31 and 32 closely. The centers of the arcuate slots 49 and 51 are spaced a small distance so that the support sheet 47 is continuous across the ends 33 of the ring segments 31 and 32 as seen at 53, so that the sheet presents a die-cut web for holding the ring segments 31 and 32 in spaced relationship and against lateral dis-

placement with respect to the sides 11 to 14 of the container 10.

As seen with particular reference to Figure 4, the sheet 48 underlies the sheet 47 and is held in properly spaced relationship with respect to the sheet 47 by upturned flanges or tabs 54 which extend along the inner sides of the sidewalls 12 to 14 of the container 10. The upturned flanges bear against a tray 56 having sides 57 extending along the inner sides of the walls 11 to 14 and bearing against the inside of the top closure of the carton 10.

The trays 34 and 56 and the divider pad 46 define a pair of compartments 40 and 50 within the container body 10, and it will be seen that ring segments 27 and 28 are isolated within the compartment 40 from ring segments 31 and 32 which are isolated within the compartment 50.

It will be seen that the support sheets 37 and 38 at all times afford a positive means for preventing lateral shifting of the ring segments 27 and 28, at the same time preventing any possibility of the ring segments 27 and 28 overturning or canting about their bottom surfaces. Since the two support sheets 37 and 38 are limited in movement in a direction normal to their substantial planes by the flanges 43 and 44, bearing respectively against the inverted tray 34 and the divider pad 46, there will at all times be at least one of the support sheets affording support against lateral movement of the ring segments 27 and 28. Since the arcuate slots formed in the sheets 37 and 38 are of such dimension as to closely contact the sides of the ring segments 27 and 28, there is little if any movement of the support sheets 37 and 38 with respect to the ring segments 27 to 28, since there is sufficient frictional engagement to prevent such movement. However, in the event there is such movement normal to the plane of the support sheets 37 and 38, the flanges 43 and 44 will limit such movement, so that sheet 38 will be supported by its flanges 43 on the inverted tray 34, or so that sheet 37 will be supported by its flanges 44 on the divider pad 46 in case the carton is inverted.

It will likewise be seen that the support sheets 47 and 48 will function in a manner similar to the support sheets 37 and 38, so that at all times the ring segments 31 and 32 will be provided with lateral support by either of the support sheets 47 or 48 depending upon whether the carton 10 is inverted or in the position shown in the several figures.

As shown in the figures, ring segments 31 and 32 are positioned 90° to the ring segments 27 and 28 so that a certain amount of bridging support action is had across the spaced ends 29 or 33 depending upon whether the carton 10 is inverted or not. Such disposition of the ring segments also tends to prevent any rocking of the tiered split support rings within the carton 10.

Referring now particularly to Figures 1 and 3 of the drawings, there is shown a number of radially directed arrows in the plane of the support sheets 47 and 48 respectively. These arrows are intended to represent vectorially the uniform pressure transmitted by the support sheets 37, 38, 47 and 48 into the split ring segments 27, 28, 31 and 32 by blows incident against the sides of the container 10.

It will be noted that the inverted tray 34 and the upper tray 56 space the extreme planar surfaces of the ring segments from the top and bottom of the container 10, and that the usual blows against the top and bottom of the container 10

will be distributed through the top and bottom closures into the side walls 11 to 14.

The preferred embodiment of the invention is shown as being adapted to provide for the packaging of a pair of split ring assemblies, but it is contemplated that only one of the pair of split ring assemblies may be packaged. In such a case the split ring segments 27 and 28 are supported upon the inverted tray 34 and held in position against lateral displacement by the support sheets 37 and 38. The tray 56 is then positioned atop the ring segments 27 and 28 so that tabs 57 bear against the underside of the top closure of the carton 10, the upturned tabs 44 of sheet 38 bearing against the underside of the tray 56. The movement of the support sheets 37 and 38 in this embodiment of the invention is limited by the trays 34 and 56, so that the ring segments are at all times afforded lateral support by the support sheets 37 and 38.

In this form of the invention, which contemplates packaging one pair of split rings only, complete isolation and spacing of the ring segments against blows incident to transportation and handling is also achieved.

The improved container according to the present invention has been found to almost completely eliminate breakage to articles of the kind described herein, while prior to employing a packaging arrangement as described herein the losses in shipping were very high. The package described herein is completely formed from sheet material which is modified by the most simple die cutting and scoring operations.

While the invention has been described in terms of preferred embodiments which the invention may assume in practice, its scope is not intended to be limited by the embodiment shown, nor otherwise than by the appended claims.

I claim:

1. An improved package including a pair of frangible, refractory, split fire-pot ring segments, said package comprising a container body having side walls and top and bottom closures, a first inverted tray holding said pair of ring segments in position spaced from the bottom closure of said container body, a second tray resting upon said ring segments and spacing said ring segments from said top closure, and means for holding said ring segments against lateral displacement within the compartment formed by said trays and container and for holding said ring segments in mutually spaced relationship, said means comprising a pair of interfitting U-shaped support sheets in said compartment, each of said support sheets having its substantial plane spaced from the other and having arcuate slots cut therein of such dimension as to closely fit and yieldingly seize said spaced ring segments, one of said support sheets having tabs extending along opposite walls of said container body and bearing against said second tray, and the other of said support sheets having tabs extending in an opposite direction along another pair of opposite walls of said container body and bearing against said inverted tray.

2. In the art of packaging frangible fire-pot rings of the split variety consisting of mating pairs of half-ring segments, the combination, 70 with a container having a plurality of pairs of oppositely facing sidewalls, and oppositely facing top and bottom walls adjacent thereto, of improved ring-supporting and protective means comprising, to wit: an inverted bottom tray disposed on the inside bottom wall of said con-

tainer; a first pair of said segments disposed on said bottom tray; a divider pad resting on said first pair of segments and dividing the container interiorly into upper and lower compartments with said first pair of segments situated in the lower compartment; a second pair of said segments disposed upon said divider pad in the upper compartment; and support-sheet means for each pair of segments to hold the same against lateral displacement and secure the several segments of each pair in predetermined spaced relation to each other and in approximate concentricity relative to an axis normal to said sheet means and divider pad; said support sheet means comprising a pair of support sheets in each said compartment, each sheet of a pair having its substantial plane normal to said axis and spaced from the plane of the companion sheet, and both sheets of each pair having two arcuate slots cut therein in approximate concentricity to said axis and so positioned and dimensioned that each slot closely fits and yieldingly seizes one of the segments of the pair engaged thereby, a first one of the support sheets in the lower compartment having a pair of oppositely facing pendant marginal tabs respectively extending along, and engaging, a first pair of said opposite walls of the container and bearing downwardly against said bottom tray; and the companion sheet of said first pair in the lower compartment having a similar pair of tabs extending in the opposite direction toward said upper compartment but along another pair of said opposite walls of the container adjoining the first-mentioned pair, and bearing upwardly to abut said divider pad; and a second pair of support sheets identical to said first pair and seizing the second pair of segments in the upper compartment in like manner to the first pair as aforesaid, and further having one pair of pendant tabs on a first support sheet bearing downwardly against said divider pad, and a second pair of tabs on the companion sheet bearing upwardly toward the top wall of the container; together with a top tray inverted in the upper compartment and interposed between the top wall of the container and said second pair of segments to abut said last-mentioned upwardly projecting tabs.

3. A packaged fire-pot ring assembly including at least one pair of semi-cylindrical fire-pot rings, seized by a pair of U-shaped paperboard support sheets each having a flat central portion situated between a pair of rectangularly offset marginal tabs formed integrally therewith, said
